TIME CONTROLLED PROGRAM SELECTOR
FOR RADIO SETS

Lillian Yancey Huffaker, Los Angeles, Calif.

Application May 8, 1933, Serial No. 670,006

1 Claim. (Cl. 250—20)

This invention relates to a time controlled program selector for radio receiving sets. It is an object of the invention to provide a clock-operated chart for the display in proper succession of the programs to be presented at predetermined times by a selected group of stations, said chart operating as a master switch for controlling circuits forming portions of the condenser operating mechanism whereby selected stations can be brought in at predetermined times, and in predetermined succession.

It is another object of the invention to provide simple but efficient mechanism by means of which any selected station can be tuned in automatically at a predetermined time and to provide additional means by which any station within the range of the receiver can be tuned in by manual operation of the dial without interference from the automatic mechanism.

A still further object is to provide an apparatus of this character utilizing a program chart which can be in the form of a web adapted readily to be placed into or removed from position, it being possible to utilize a web having a program extending over one or more days so that after the web has been placed in the apparatus and coupled to its clock mechanism, no further attention need be given to the radio receiver during the period covered by the program chart from which selections have been made.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawings the preferred form of the invention has been shown.

In said drawings:

Figure 1 is a front elevation of one form of radio receiver equipped with the present improvements.

Figure 2 is a horizontal section taken substantially on the line 2—2, Figure 1, the dial and condenser being shown in plan, parts being broken away.

Figure 3 is a section on line 3—3, Figure 2 showing in front elevation most of the mechanism illustrated in said figure.

Figure 4 is a section on line 4—4, Figure 2.

Figure 5 is a section on line 5—5, Figure 2.

Figure 6 is a section on line 6—6, Figure 2.

Figure 7 is an enlarged elevation of one of the condenser controlling magnets, parts being broken away.

Figure 8 is a plan view thereof.

Figure 9 is a front elevation of the sweep of the tuning mechanism.

Figure 10 is a side elevation thereof.

Figure 11 is an enlarged section through the coupling of the alining condenser shafts.

Figure 12 is an elevation of one form of motor reversing switch which may be used.

Figure 13 is an enlarged elevation of the automatic switch which can be used with the set for starting and stopping the operation thereof.

Figure 14 is an elevation of the time clock operated controlling web displaying available programs.

Figure 15 is a section on line 15—15, Figure 14.

Figure 16 is a detail view of a means for holding the movable contact members which cooperate with the web.

Figure 17 is a plan view of an intermediate portion of the web.

Figure 18 is a plan view of a portion of one end of the web showing its reduced width.

Figure 19 is a section on line 19—19, Figure 14.

Figure 20 is a view showing in diagram the several circuits forming a part of the present invention.

It is to be understood that many modifications of the present invention can be utilized and that the apparatus illustrated is merely one of many forms which could be used in carrying out the invention. For example various types of radio receivers can be used; clocks driven by springs, weights, electricity, etc. can be employed; the clock and the web operated thereby can be located at any desired point within or remote from the set; the program web can be of any length or width found best suited to meet the requirements; and the complete apparatus can be built into the set or can be constructed in the form of an attachment to be applied to a set. For the purpose of illustrating the essential features of the invention one form only has been illustrated and will be described.

In the structure illustrated the casing of the set has been indicated at 1 and supported in this casing is a speaker 2 in front of which can be located the usual screen 3 having an ornamental grill 4. In this illustrated structure the grill constitutes the support for the frame 5 of the clock operated mechanism. In one side of this frame is located the clock mechanism indicated generally at 6, the face 7 of the clock being exposed.

through the front of the frame as shown in Figure 1. The other side of the frame contains the mechanism which is driven by the clock and a portion of this mechanism is visible through the 5 open face of the frame as shown. Normally the frame 5 is fastened in closed position against the grill 4. However, as the frame is movably connected to the grill, as by means of a hinge 8, it can be swung downwardly, for example, until brought 10 to a substantially horizontal position. The mechanism of the clock and the mechanism which is driven by the clock are preferably arranged in a housing 9 carried by the frame and the back of this housing can be closed by a removable 15 cover 10 which normally serves to exclude dust. When the frame 5 is swung to open position, this cover 10 can be reached readily and removed from housing 9, thereby affording access to the interior of the housing and the mechanisms contained 20 therein.

The clock 6 has a driven shaft 11 provided at one end with a clutch member 12. This shaft can be shifted longitudinally by a knob 13. It is intended that the shaft rotate at a predetermined 25 speed relative to the movement of the minute hand of the clock so that the mechanism driven by the clock through this shaft 11 will operate in a predetermined timed relation with the clock.

The driven mechanism in the housing 9 can 30 be the same as that disclosed in my Patent 1,911,448, dated May 30, 1933, or can be of a simplified construction such as illustrated in the drawings. In the illustrated structure spools 14 and 15 are mounted for rotation in opposite end 35 portions of the housing, each spool being provided with a knob 16 whereby it can be rotated readily in either direction when the cover 10 is removed. Spool 15 has disc-like heads 17 and 18, one of which 17, constitutes a pulley for receiving motion through a crossed belt 19 from a pulley 14' 40 constituting one head of spool 14.

Shaft 20 has a clutch member 21 adapted to 45 be engaged by and to receive motion from the clutch member 12. This shaft carries a roll 22 provided with short radial teeth 23, and extended transversely of the housing adjacent to the spool 14 is a guide roll 24.

The program chart to be used in connection 50 with this apparatus can be of the form illustrated, for example, in Figures 14 and 17. This chart consists of an elongated web 25 provided adjacent to its edges with longitudinal series of openings 26 into which the teeth 23 are adapted to project. The web has its ends detachably connected in any suitable manner to the respective spools and is looped about rollers 22 and 24 so that a portion of the web at all times will be stretched close to and parallel with the front or open face of frame 5. One end portion of the web has its 55 sides cut away longitudinally as at 25'.

When the two shafts 11 and 20 are coupled together the roll 22 will be driven at such a speed 60 as to cause a predetermined length of web 25 to pass a given point during a predetermined period of time. At the same time that the web is thus being actuated it will pull upon and rotate spool 14 and cause motion to be transmitted through pulley 14', crossed belt 19 and pulley 17 to spool 15, thereby to wind the web on spool 15. The belt can slip to compensate for any 65 variation between the speeds of rotation of the spools.

The web is provided with transverse lines 27 70 which divide the web into time periods. The 75 spaces between these lines representing the dif-

ferent time periods can be designated by indications of those times of the day with which they are associated. For example one space 28 between two of the lines can be designated at one side by "1.30 P. M."; the next adjoining period 5 can be designated "1.45 P. M."; the next period can be designated "2 P. M."; etc. to the end of the web, fifteen minutes being assigned in the illustrated form to each designated period.

In each of the time designated spaces there 10 can be displayed the letters of those stations capable of selection by the apparatus, the letters of the stations all being located in a column as shown in Figure 17 and there being displayed beside the letters of each station the particular 15 program to be presented during that particular time period.

The tape is divided into longitudinal columns by longitudinal lines 29. One of these columns 30 is provided for each of the stations designated 20 on the web. Another column, 31 can be used in the control of the starting mechanism of the apparatus while another column 32 can be used to control the stopping of the apparatus. Along each of the lines 27 or at any other suitable 25 points within or adjacent to each of the time spaces 28 are removable tabs 33 which can be divided by scored or perforated lines which weaken the tape and permit the tabs to be removed 30 readily when desired. One of these removable portions is located in each column 30, 31 and 32 and, as before stated, one set of these removable tabs is provided for each time space 28. For the purpose of convenient identification each 35 station can be provided with a designating numeral as indicated at 34 and the column 30 assigned to each station can be identified by the corresponding numeral appearing on the tab 33 in said column. For example station KOX has the number 3 associated with it. The number 3 40 also appears on the tabs 33 in one of the columns 30. Thus the user of the web can readily locate at any point and in any time space 28 the particular column associated with a particular station.

Arranged back of the web 25 so as to be slidably engaged thereby is a contact bar 35 and carried by this bar but insulated therefrom are stationary contacts 36 and 37 located back of the respective columns 31 and 32.

Extending across the front of the web 25 is a supporting bar 38 of insulating material and with this bar cooperates a strip 39 also of insulating material whereby a series of resilient contact fingers 40, 41, 42, 43, 44, 45 and 46 can be held 55 securely in properly spaced relation, each finger being formed preferably with a rounded terminal 47 for sliding engagement by that portion of the web engaging the contact bar 35.

The mechanism thus far described is all located in the housing 9 and while this housing has been illustrated as located at a particular point in the receiving set it, as hereinbefore stated, can be located at any other point on the set or even at a point remote therefrom.

The interior of the receiving set has been shown in part in Figure 2, a housing for the tubes being indicated at 48 while the transformer has been indicated at 49 and the rectifier at 50. A portion of the condenser has been shown at 70 51 and the shaft 52 of the condenser has the usual graduated dial 53 for display through the opening 54 while a knob 55 can be used for actuating the condenser. As shown in Figure 4 the shaft 56 of knob 55 can be provided with a pulley 75

57 for actuating an endless belt 58 which is extended over a guide sheave 59 to a pulley 60 secured to the shaft 52. Thus by rotating the knob the condenser and its dial 53 can be operated in the usual manner.

Secured to shaft 52 so as to rotate therewith is a sweep 61 the outer end of which is provided with normally spaced resilient contact fingers 62 insulated from each other and from the sweep. 10 Obviously during the rotation of the condenser shaft 52 this sweep will be swung in an arc back and forth, according to the direction of movement of the dial 53.

Adjacent to the path of movement of sweep 15 61 is an arcuate supporting bar 63 mounted on a suitable bracket 64 and provided with a longitudinal slot 65. In this slot are adjustably mounted electro-magnets 66. One of these magnets is provided for each of the stations adapted 20 to be tuned in by the apparatus and each electro-magnet has a spring pressed armature 67 which is held normally spaced from the core 68 of the magnet as shown by full lines in Figure 7. An arm 69 is extended from and moves with the 25 armature and is preferably extended back so as to normally lie substantially parallel with the magnet. This arm has a projection 70 extending from its free end portion.

The sweep 61 is adapted to swing in a path 30 close to the armature 67 and the contacts 62 thereon are adapted to travel in a path close to the free ends of the projections 70 when these projections are in their normal positions. Obviously, therefore, when none of the magnets is 35 energized and all of the armatures are located as shown by full lines in Figure 7, the sweep 61 can move back and forth with its shaft without bringing contacts 62 against any one of the projections 70.

40 The magnets 66 are spaced apart relative to each other the same relative distances as are those graduations on the dial 53 which designate the stations to be tuned in. Therefore, when dial 53 is rotated to tune in station KOX, the contact fingers 62 will be brought to position for engagement by the projection 70 of magnet 66 belonging to the said station KOX.

An electric motor 71 is suitably located in the housing 1 and is adapted to transmit motion 50 through suitable speed reduction gearing to a supplemental condenser shaft 72 which aligns with shaft 52. This speed reduction mechanism can consist of a worm 73 on the motor shaft meshing with a worm gear 74 which, in turn, is 55 carried by a shaft 75. A worm 76 on this shaft meshes with a worm gear 77 on the shaft 72.

Shaft 52 has a coupling disc 78 secured thereto and provided with an opening 79. Another disc 80 is keyed on shaft 72 so as to rotate therewith 60 but slide thereon. This disc 80 carries a spring pressed coupling pin 81 which projects normally from the disc so as to snap into opening 79 when brought into register therewith.

Disc 80 has a hub 82 provided with an annular 65 groove 83 and projecting into the groove is a forked arm 84 extending from a slide 85 which is mounted for reciprocation in suitable guides 86. The slide constitutes a rack which is constantly engaged by a gear 87 on shaft 88 of a clutch controlled by a gear 89. Thus by rotating the knob to the right in Figure 1 the disc 80 will be shifted 70 to the right so as to withdraw pin 81 from opening 79 and thereby uncouple the disc 80 from the disc 78. By turning the knob to the left disc 80 75 can be brought against disc 78, thereby pushing

the pin 81 back against the action of its spring until such time as the pin arrives in line with opening 79 whereupon the pin will snap into the opening and couple together the two discs and their shafts.

A reversing switch can be used for reversing the motor 71 each time the condenser is brought to either limit of its movement. Obviously various types of reversing switches or the like can be used. In Figure 12 a double switch has been 10 shown with spaced movable contacts 90 and 91 and with stationary contacts 92, 93 and 94 for engagement thereby. The movable contacts are adapted to shift in unison and are provided with an arm 95 movable about the fulcrum 96 of one 15 of the contacts. This arm has a pin 97 pivotally connected to it and slidable in a guide 98. A spring 99 exerts a constant thrust against the pin and, through the pin, against the arm 95. Thus this arm when moved to a dead center will place the spring under compression but as soon as it passes the dead center the spring will expand and snap the arm and the movable contacts of the switch to one extreme position. Operation of the arm 95 can be effected by cam fingers 100 20 25 which are carried by shaft 72 and extend in opposite directions therefrom. The two cams are so located relative to each other that while shaft 72 is being rotated in one direction one of these cams will come against arm 95 and move it toward its dead center. As soon as the movable condenser reaches its extreme position through the rotation of shaft 72 coupled thereto, arm 95 30 will pass its dead center and be snapped abruptly to its new extreme position, thereby to reverse 35 the switch and the rotation of the motor controlled thereby. When shaft 72 is rotated in the opposite direction a similar action will take place as soon as the condenser reaches the limit of its movement, thereby again reversing the motor. 40

The switch used for turning on and off the current to the set can be of any preferred construction. One form of switch to be used for this purpose has been illustrated in detail in Figures 3, 13 and 20. This switch includes oppositely disposed solenoids 101 and 102. The armatures 103 of the solenoids are pivotally connected to a switch arm 104 which is secured to and movable with the shaft 105 of the switch control knob 106. A spring pressed pin 107 is pivotally connected to arm 104 and is adapted to shift it to the left or to the right after it passes a dead center. Switch arm 104, when in one extreme position, engages two contacts 108 and 109 so as to electrically connect them. When the arm is in its other extreme position the circuit through these contacts is 50 broken as shown in Figure 20.

The various parts of this apparatus can be 55 electrically connected as shown in diagram in Figure 20. As therein indicated each of the magnets 66 is electrically connected to one of the fingers 41-45 inclusive and all of the magnets are, in turn, electrically connected to one of the contact fingers 62 and to the magnet 110 of a relay, this magnet being also electrically connected to the other contact finger 62. Direct current is conducted from the rectifier 50 to one side of the magnet 110 and is also conducted to the contact bar 35. The armature 111 of the relay can be held by a spring 112 so as to normally 60 press together two contacts 113, thereby closing the circuit to the speaker 2 through the set 48.

The armature 111 is electrically connected to the intermediate contact 94 of the reversing switch and the contact 114 from which the ar- 70 75

ture is normally spaced, is electrically connected to one terminal of a plug 115. This contact is also electrically connected to one terminal 116 of the transformer 49 and to one terminal 117 of the set 48. The other terminal of the plug 115 is electrically connected to contact 108 while contact 109 is electrically connected to the terminal 118 of set 48, terminal 119 of transformer 49, to the field 120 of motor 71 and to the contacts 92 and 93 of the reversing switch. The movable contacts 90 and 91 of this switch are connected to the respective brushes of the motor as shown.

A second plug is preferably used in connection 15 with the apparatus and has been indicated at 121. One terminal of this plug is electrically connected to the two contacts 36 and 37. The other terminal of plug 121 is electrically connected to the two solenoids 101 and 102. Solenoid 101 is also connected electrically to contact finger 40 while solenoid 102 is electrically connected to contact finger 46.

When it is desired to use this apparatus the frame 5 is opened, the back cover 10 is removed 25 and shaft 11 is shifted longitudinally to disengage it from clutch or coupling member 21. A web 25 containing the printed program covering the period during which the apparatus is to be used is prepared by removing selected tabs 33 for the 30 purpose of starting and stopping the operation of the set at desired times and for bringing in selected programs. For example should it be desired to start the set at 1.30 P. M. tab a in the starting column 31 and on the "1.30 P. M." line 35 27 will be removed. If it is desired at that time to listen to a fifteen minute program of station KAC, tab number 4 on the same line would be removed because the number of this tab corresponds with the number assigned to that station 40 and is located in the proper column for bringing in the station. If, after a fifteen minute program on station KAC, it should be desired to listen to a fifteen minute program on station KVD, the user removes tab 2 from line 27 belonging to the "1.45 45 P. M." time interval. This preparation of the web can be continued for the purpose of bringing in any desired programs during the day or during several days if the web is of sufficient length and whenever it is desired to stop the operation of the set a tab 33 can be removed from column 32 at the proper point.

Following the selection of the desired programs in the manner pointed out the web is placed in engagement with spool 14 and wound thereon. 55 The free end of the web is then placed over roll 24, inserted between contact bar 35 and the several contact fingers 40 to 46 inclusive, looped in engagement with roller 22 so that the teeth thereon will enter certain of the openings 26, and 60 then attached to the spool 15. This spool 15 can be turned to wind the web thereon until the time indicated by the fingers 40-46 in cooperation with the markings on the web corresponds with the time indicated by the clock. When the parts 65 are thus assembled the shaft 11 is shifted longitudinally so as to couple it to shaft 21 and the frame 5 is moved to closed position.

The web will now be driven slowly but positively by the clock mechanism and if the set is 70 to begin operating at 1.30 P. M. nothing will occur until that hour. As soon as the selected time arrives the opening left by the removal of tab a will arrive between contact finger 40 and contact 75 36. Instantly a circuit will be established from plug 121 through these contacts to the solenoid

101 which will be energized and pull the switch arm 104 from the position shown in Figure 20 to the position shown in Figure 13, thereby closing the circuit between the contacts 108 and 109. This action results in establishing a circuit from the plug 115 to the set and to the supplement transformer 49 and rectifier 50.

If, as already stated, the program of station KAC is to be brought in simultaneously with the starting of the set, the opening formed by the removal of tab number 4 on the "1.30 P. M." line 10 will arrive between contact bar 45 and finger 44 belonging to said station, thereby effecting a contact between these parts simultaneously with the contact between finger 40 and contact 15 36.

As soon as this contact is effected a circuit 20 is established from the finger 44 to magnet 66 connected thereto and thence to magnet 110. As a result of this action the selected magnet 66 will attract its armature 67 so as to move projection 70 to the dotted line position shown in Figure 7. Simultaneously with this action is the attraction of armature 111 by magnet 110. This attraction results in releasing one of the contacts 113 so as to break its connection with the other contact 113 and cut out the speaker from the set. At the same time armature 111 moves into engagement with contact 114 and closes the circuit to the motor 71. Thus shaft 72 will be caused to rotate slowly in one direction and if the shifted projection 70 is not in the path of contact fingers 62 the rotation of the shaft will continue until the movable condenser reaches one limit of its movement. At this time one of the cams 100 will reverse the position of switch arm 95 and cause the reversing switch to shift off of contact 92, as shown in Figure 19, into position on contact 94. Consequently the direction of rotation of the motor 71 will be reversed instantly and shaft 72 as well as shaft 52 coupled thereto 35 will be rotated in the opposite direction. This movement will continue until one of the contact fingers 62 comes against the projection 70 which has been shifted into the path thereof. This will result in the two contacts 62 coming together and the current from the rectifier will be shunted around the relay magnet 110. Consequently this magnet will be de-energized and its armature 111 will be released. As the armature moves back to its normal position under the 40 action of spring 112 it breaks the circuit to the motor which immediately ceases to function. The armature also presses the contacts 113 together to re-establish the circuit to the speaker.

When the shafts were rotated by the motor 55 as before explained and the contacts 62 brought against the projection 70, said shafts and the condenser 51 as well as the dial 53 were rotated to such a position as to tune in the selected station and as the operation of the motor stopped 60 as soon as the selected station was reached, due to the shorting of the circuit through contacts 62, the condenser will remain in the position to which it has been moved and the selected station thus will be brought in.

During the foregoing operation the web is being moved slowly by its clock mechanism and the selected magnet 66 will remain energized until the opening produced by the removal of the number 4 tab has passed from between finger 44 70 and contact bar 45. As soon as the opening has thus passed the web will break the circuit between the finger 44 and bar 35, magnet 66 will become de-energized, and projection 70 will drop out of the path of the contact fingers 62. 75

The program of the selected station will continue to come in until the opening provided in the web for the next selected station arrives at the proper time between the contact bar 35 and the contact finger belonging to said station. At that time the same operation heretofore described will take place and the condenser will be operated by the motor until the projection 70 belonging to the selected station has interrupted 10 the movement and changed the circuits as explained.

Ultimately and after any predetermined number of changes of stations the opening in the stop column 32 will arrive between finger 46 and contact 37. This will result in closing the circuit to the solenoid 102. Consequently switch arm 104 will be moved to the position shown in Figure 20, thereby breaking the power circuit through contacts 108 and 109 and shutting off 20 the set. Thereafter the cut-away side portions 25' of the web will arrive at the roll 22 so that teeth 23 will no longer drive the web. Consequently the web will stop with all contact fingers 40-46 resting thereon and all circuits will remain 25 broken.

Should it be desired at any time to tune the set without relying upon the automatic features, it would be necessary simply to turn the switch knob 106 so as to swing arm 104 into engagement with the contacts 108 and 109. By turning the clutch knob 89 to the right in Figure 1 its gear 87 would shift slide 85 laterally and cause arm 84 to move hub 82 and disc 80 away from disc 78. This would result in the uncoupling of the 30 two discs and thereafter the dial 53 could be rotated back and forth in the usual manner by 35

means of the knob 55. Thereafter, following the reversal of the knob 87 the operation of the shaft 12 by the motor would bring the pin 81 ultimately into position to snap into opening 79, thereby resulting in the automatic recoupling of the two 5 shafts and the subsequent automatic tuning of the set as heretofore explained.

The set can be provided with an automatic volume control or said control can be regulated by a means under the control of a knob 122. 10

What is claimed is:

In a radio receiving set the combination with a condenser shaft and a condenser thereon, of a reversible electric motor, mechanism operated thereby for rotating the condenser shaft, a reversing switch for the motor, means movable with the condenser for operating the switch upon the completion of the movement of the condenser in either direction, thereby to reverse the rotation of the motor and condenser, a sweep movable 20 with the condenser shaft, a series of electromagnets adjacent to the path of the sweep, selective means for energizing any one of the magnets, and means operated by each magnet when energized, for stopping the movement of the 25 sweep and condenser and breaking the circuit to the motor, said means including a spring pressed armature, a pivoted arm carrying the same, a projection on the arm, and contacts on the sweep included in a circuit to the motor, and a speaker 30 circuit, said contacts constituting means for engagement by the projection when the magnet is energized thereby to shift the contacts together to break the motor circuit and close the speaker circuit. 35

LILLIAN Y(ANCEY) HUFFAKER.
